CONTROL MECHANISM FOR THE FLUID
PRESSURE OPERATING MOTOR OF
PRESSING MACHINESEdmund N. Neckel, Cincinnati, Ohio, assignor to
The American Laundry Machinery Company,
Cincinnati, Ohio, a corporation of Ohio

Application October 16, 1948, Serial No. 54,988

6 Claims. (Cl. 121—38)

1

This invention relates to two-hand control mechanism for garment presses of single motor form.

One object of the invention is to provide improved safe control mechanism of special form so arranged that upon operation of the two manuals, right and left hand, a master valve is actuated and the operating servomotor is thereby energized to safely close the press and permit the manuals to be released, whereupon the master valve is held or maintained in pressure position until purposely released by the operator to open the press.

Another object is to simplify the control mechanism by dispensing with valve devices and operators therefor heretofore regarded as essential, but without loss of sensitivity or in any way interfering with press operation and control.

Still another object is to provide improved valve control mechanism of the character and for the purposes stated in which the master valve serves as its own maintaining device, subject to operator control for both closing and opening the press.

Another object is to provide an improved press control including valves and valve devices which are extremely sensitive, responding to a light, momentary touch for release purposes but requiring sustained effort of both hands for the closing operation, for safety purposes.

Further objects of the invention in part are obvious and in part will appear more in detail hereinafter.

In the drawings, Fig. 1 represents diagrammatically one arrangement of valve control embodying the invention, as applied to a press, two of the valve devices being shown in section on the lines 1—1, and 2—2, Fig. 2;

Fig. 2 is a front elevation, partly broken away and in section, of the main or right-hand valve unit;

Fig. 3 is an enlarged fragmentary sectional view of the valve actuating and maintaining parts, but showing them in maintaining position; and

Fig. 4 is a fragmentary sectional view on the line 4—4, Fig. 1.

The garment press shown conventionally for purposes of illustration requires but brief description. It comprises a frame 10 supporting the stationary lower pressing member or buck 11 and on which is pivoted a two armed lever 12 supporting the cooperating upper pressing member or head 13. The actuating motor is a single acting fluid pressure servomotor 14, the piston 15

2

and rod 16 of which close and open toggle members 17 extending from lever 12 to the frame. Tension springs 18 bias the press to open position.

5 The controlling valve mechanism includes three valve devices, marked respectively A, B and C in Fig. 1, two of which, A and B, are combined as a single unit shown in Fig. 2. Section plane 1—1, Fig. 2, is that of device A and 10 section 2—2 of device B.

In a general way the present control mechanism consists of a normally closed inlet valve for the operating motor, a manually controlled servomotor for opening that valve, an exhaust valve for the motor which also serves to maintain the pressure in the motor after it is safely closed, and operator controlled means for opening the exhaust valve to release the motor.

Referring to Fig. 1, fluid pressure (compressed air) from a suitable source (not shown) is conducted by pipe 19 to a supply chamber 20 and through filter screen 21 to a passage 22 having two branches 23, 24.

25 Branch 23 is connected by pipe 25 to the supply chamber for the combined inlet and exhaust valve 26, of valve device A, having an exhaust port 27 and operated by pivoted manual 28. Upon operation of said valve, pressure flows through pipe 29 to a similar valve, marked generally C, having an operating manual 28a, and then through pipe 30 to the chamber of a servomotor, shown as including a piston 31. This is slidably mounted upon the stem of a normally open exhaust valve 32 working in chamber 33 and arranged when seated to close an annular exhaust channel 34 beneath the valve leading to an outlet 35 (Fig. 4) to atmosphere preferably packed with sound deadening or muffling material 36. Chamber 33, beneath the valve, also 35 communicates with a passage 37, in which slides a longitudinally grooved rod 38, which at one end abuts valve 32 and at its opposite end the normally closed inlet valve 39, biased to its seat by spring 40. Inlet valve 39 works in a chamber 41 connected by passage 42 and adjustable needle valve 43 to the second branch 24 of passage 22.

Passage 37, in which rod 38 slides, communicates by way of pipe 44 with the chamber of 50 motor 14 on the pressure side of the piston 15 thereof. Said chamber is provided with a side port or opening, uncovered when the piston passes it, at a point corresponding to safe closed position of the press. This port communicates by pipe 45 with the supply chamber 46 of a nor-

mainly closed exhaust valve 47 operatable by manual 48 and having an exhaust port 49 communicating by pipe 50 with the atmosphere outlet 35 before referred to.

Chamber 46 communicates by passage 51 with chamber 33.

Pipe 52, connected to chamber 41, supplies a connection for the conduction of pressure to a second press operated in tandem with the one here described.

The operation is as follows:

Fig. 1 illustrates all parts of the press and control mechanism in idle position. In other words, the press is open, inlet valve 39 is closed, the manually controlled inlet valves are also closed, and the operating motor 14 is open to exhaust.

Upon simultaneous depression of the two manuals 28, 28a of the valve devices A, C, pressure flows from the supply pipe 19 through valves A, C, to pipe 30 and thence to the chamber in which piston 31 slides. Said piston moves over, to the left in Fig. 1, carrying with it the exhaust valve 32, rod 38 and the inlet valve 39, closing the exhaust valve and opening the inlet. So long as both manuals are held depressed, the pressure will continue to flow in the manner described, holding the inlet valve open and the exhaust valve closed.

Opening of inlet valve 39 permits pressure to flow from passage 22 by way of its second branch 24 to chamber 41, thence through the open inlet valve and by way of pipe 44 to the pressure side of the piston 15 in motor 14. The piston moves over, moving the head 13 downwardly toward pressure relation with the bed.

If either hand is removed from a manual before the press is safely closed, the valve parts return to their original positions, the motor is opened to exhaust by way of passage 34, and the press opens. However, if the manuals are held depressed until the piston 15 passes the port in the side of the cylinder, the pressure flows through pipe 45 to chamber 46 and by way of passage 51 to the chamber 33, on the pressure side of the outlet valve 32 therein. When this valve is seated, its effective area is that of the annular ring between its two sealing rings 32a, one on each side of the exhaust passage beneath it, and the pressure in chamber 33, on that area of the opposite face of the valve, is great enough to maintain the exhaust valve closed and the inlet valve open, against all opposing forces, including the fluid pressure effects and the bias of spring 40.

Now, the operator can remove his hands from the manuals 28, 28a, and the press will remain closed, under full pressure, with the inlet valve 39 open and the exhaust valve held closed.

Of course, so long as the operator holds down the manuals 28, 28a, which supply pressure to the right-hand end of the chamber 33 in which the piston 31 travels, and after the piston 15 has passed the port in the side of its cylinder and pressure becomes effective on the other face of piston 31, said piston remains in its advanced position, abutting the closed exhaust valve 32. But as soon as the manuals 28, 28a are released, the pressure in chamber 33 which advanced piston 31 is evacuated and the piston returns to its original position, shown in Fig. 3, leaving the exhaust valve 32 closed and maintained closed by the pressure now ahead of the piston.

When it is desired to open the press, the manual 48 is depressed, thus opening chamber 33 to exhaust by way of the now open exhaust

valve 47, pipe 50 and the exhaust outlet 35. Promptly, the balance of opposing forces effective upon valve 32 is disturbed and the two valves 32, 39 move to their original idle positions with the exhaust valve open and the inlet valve closed. The pressure within the chamber of motor 14 finds a path to atmosphere both by way of pipe 45 and the open exhaust valve 47 to pipe 50, or to outlet passage 34, or both, and by way of pipe 44 to the chamber 37 and to outlet passage 34. As soon as the retracting piston 15 passes the port in the side of the cylinder, the pressure chamber of the motor completes its evacuation by way of pipe 44, but the chamber 33 remains open to exhaust, even though manual 48 is released, by way of pipe 45 and the atmospheric side of the piston 15 in cylinder 14 and its usual outlet to atmosphere.

If push button 48 is released before piston 15 moves back past the cylinder port, reactivation of the valve mechanism is prevented by the non-piston form of valve 32 in conjunction with the exhaust channel 34, now uncovered.

Thus, a momentary depression of manual 48 accomplishes the movement of exhaust valve 32 to open position and the closing of inlet valve 39, with no possibility of either valve returning to its "on position," insuring opening movement of the press and without any possibility of a closing movement thereof after the release operation has been initiated.

In the arrangement described, the two valves 39 and 32 cooperate as inlet and exhaust valves for the chamber of motor 14. However, valve 32 also is effective as an abutment to maintain itself closed and the inlet valve open, when they are actuated to those positions, by reason of the pressure applied to valve 32 in chamber 33. Thus, the complete control mechanism in effect consists of three valves each of the combined inlet and exhaust variety, two of which, A and C, serve as controllers for the third, B, together with the single exhaust valve 47, operation of which accomplishes movement of the third to release position.

It should be noted that a definite relation preferably should exist between the cross-sectional areas of the entrance port M to chamber 46 and the outlet port N from the opposite end of said chamber to passage 49 and the outlet pipe 50. The entrance port M should be substantially smaller in area than the outlet port N, in order to insure instantaneous release of outlet valve 32. Preferably, the area of port N should be about four times that of the port M. Otherwise, the release of the maintaining air pressure from chamber 33 is offset by the incoming air rushing through port M, resulting either in a delayed opening of valve 32 or its failure to open at all.

Ordinarily, the size of port N is limited by some consideration of the operating force required to actuate push button 48, so that in practice a rather small port M is used. In any event, with the proper proportion between the areas of the two ports instantaneous release between valves 32 is effected upon actuation of button 48.

The mechanism as a whole is extremely simple, is delicate in operation and is certain in its results, avoiding any possible injury to the operator as a result of unintentional pressure closure after press release operation is initiated.

Other advantages of the invention will be apparent to those skilled in the art.

What I claim is:

1. Control mechanism for the fluid pressure

operating motor of a pressing machine, comprising inlet and exhaust valves having unison movement, means biasing said inlet valve to closed position and said exhaust valve to open position, means providing a chamber having an exhaust port, said exhaust valve being movably mounted in said chamber and closing said exhaust port when in closed position, an abutment in said chamber movable therein toward and from said exhaust valve, operator operated means for supplying fluid pressure to one face of said movable abutment to cause said abutment to move toward said exhaust valve and to thereby effect the closing of the exhaust valve and the opening of the inlet valve, means for supplying fluid pressure to the operating motor when said inlet valve is open and said exhaust valve is closed, a conduit controlled by actuation of said operating motor for supplying fluid pressure to the other face of said movable abutment, with consequent movement of the abutment in a direction from said exhaust valve, and for simultaneously supplying fluid pressure to said exhaust valve for the maintenance of said exhaust valve in closed position and the inlet valve in open position, and operator operated means for effecting the movement of the exhaust valve to open position and the inlet valve to closed position.

2. Control mechanism for the fluid pressure operating motor of a pressing machine, comprising inlet and exhaust valves having unison movement, means biasing said inlet valve to closed position and said exhaust valve to open position, means providing a chamber having an exhaust port, said exhaust valve being slidably mounted in said chamber and closing said exhaust port when in closed position, a piston in said chamber and slideable toward and from said exhaust valve, operator operated means for supplying fluid pressure to one face of said piston to cause said piston to move toward said exhaust valve and to thereby effect the closing of the exhaust valve and the opening of the inlet valve, means for supplying fluid pressure to the operating motor when said inlet valve is open and said exhaust valve is closed, a conduit controlled by actuation of said operating motor for supplying fluid pressure to the other face of said piston, with consequent movement of the piston in a direction from the exhaust valve, and for simultaneously supplying fluid pressure to said exhaust valve for the maintenance of said exhaust valve in closed position and the inlet valve in open position, and operator operated means for effecting the movement of the exhaust valve to open position and the inlet valve to closed position.

3. Control mechanism for the fluid pressure operating motor of a pressing machine, comprising inlet and exhaust valves having unison movement, means biasing said inlet valve to closed position and said exhaust valve to open position, means providing a chamber having an exhaust port, said exhaust valve being slidably mounted in said chamber and closing said exhaust port when in closed position, a piston in said chamber and slideable toward and from said exhaust valve, said exhaust valve having a stem along which said piston slides, operator operated means for supplying fluid pressure to one face of said piston to cause said piston to move toward said exhaust valve and to thereby effect the closing of the exhaust valve and the opening of the inlet valve, means for supplying fluid

pressure to the operating motor when said inlet valve is open and said exhaust valve is closed, a conduit controlled by actuation of said operating motor for supplying fluid pressure to the other face of said piston, with consequent movement of the piston in a direction from the exhaust valve, and for simultaneously supplying fluid pressure to said exhaust valve for the maintenance of said exhaust valve in closed position and the inlet valve in open position, and operator operated means for effecting the movement of the exhaust valve to open position and the inlet valve to closed position.

4. Control mechanism for the fluid pressure operating motor of a pressing machine, comprising inlet and exhaust valves having unison movement, means biasing said inlet valve to closed position and said exhaust valve to open position, means providing a chamber having an exhaust port, said exhaust valve being slidably mounted in said chamber and closing said exhaust port when in closed position, a piston in said chamber and slideable toward and from said exhaust valve, said piston having an axially disposed cavity and said exhaust valve having an axially disposed stem extending into said cavity, operator operated means for supplying fluid pressure to one face of said piston to cause said piston to move toward said exhaust valve and to thereby effect the closing of the exhaust valve and the opening of the inlet valve, means for supplying fluid pressure to the operating motor when said inlet valve is open and said exhaust valve is closed, a conduit controlled by actuation of said operating motor for supplying fluid pressure to the other face of said piston, with consequent movement of the piston in a direction from the exhaust valve, and for simultaneously supplying fluid pressure to said exhaust valve for the maintenance of said exhaust valve in closed position and the inlet valve in open position, and operator operated means for effecting the movement of the exhaust valve to open position and the inlet valve to closed position.

5. Control mechanism for the fluid pressure operating motor of a pressing machine, comprising a casing having a passageway therethrough for the supply of fluid pressure to said operating motor for the operation thereof, a normally closed inlet valve in said passageway and biased toward closed position for controlling the flow of fluid pressure through said passageway to said operating motor, said casing also having a chamber therein and a duct for establishing communication between said chamber and the valve discharge side of said passageway, said chamber having a base wall through which said duct extends and also having an exhaust port extending through said base wall, a normally open exhaust valve slidably mounted in said chamber and movable to closed position against said base wall to thereby close said exhaust port and said duct, means extending through said duct to cause unison movement of said inlet valve and said exhaust valve, the inlet valve being closed when the exhaust valve is open and vice versa, a movable abutment in said chamber, said abutment being movable independently of said exhaust valve and being effective, upon the application of fluid pressure to the outer face thereof, to move said exhaust valve to closed position and the inlet valve to open position, operator operated means for supplying fluid pressure to the outer face of said abutment, means controlled by said operating motor for supplying fluid pressure to said ex-

haust valve and to the inner face of said movable abutment, to thereby maintain said exhaust valve closed and to move said movable abutment in a direction from said exhaust valve, and operator operated means for moving said exhaust valve to open position, with consequent closing movement of said inlet valve.

6. Control mechanism for the fluid pressure operating motor of a pressing machine, comprising a casing having a passageway therethrough for the supply of fluid pressure to said operating motor for the operation thereof, a normally closed inlet valve in said passageway and biased toward closed position for controlling the flow of fluid pressure through said passageway to said operating motor, said casing also having a chamber therein and a duct for establishing communication between said chamber and the valve discharge side of said passageway, said chamber having a base wall through which said duct extends and also having an annular exhaust passageway surrounding said duct and extending through said base wall, a normally open exhaust valve slidably mounted in said chamber and movable to closed position against said base wall to thereby close said exhaust passageway and said duct, means extending through said duct to cause

5 unison movement of said inlet valve and said exhaust valve, the inlet valve being closed when the exhaust valve is open and vice versa, a piston 10 slideable in said chamber independently of said exhaust valve and effective, upon the application of fluid pressure to the outer face thereof, to move said exhaust valve to closed position and the inlet valve to open position, operator operated means for supplying fluid pressure to the outer 15 face of said abutment, means controlled by said operating motor for supplying fluid pressure to said exhaust valve and to the inner face of said movable abutment, to thereby maintain said exhaust valve closed and move said movable abutment in a direction from said exhaust valve, and operator operated means for moving said exhaust valve to open position, with consequent closing movement of said inlet valve.
